UNITED STATES PATENT OFFICE.

ARTHUR CROMPTON, OF MANCHESTER, ENGLAND.

MACHINE FOR FINISHING TEXTILE FABRICS.

Application filed February 24, 1927, Serial No. 170,725, and in Great Britain March 11, 1926.

This invention relates to the production of new and novel finishes on textile fabrics.

According to the invention the fabric is passed between a pattern roller of mild steel, vulcanized rubber, compressed fibre, cotton or paper or other suitable composition on which is carved or engraved a design and a heated polished metal roller geared to run at a slightly different surface speed to that of the engraved roller.

The invention will be described with reference to the accompanying drawings in which:—

Fig. 1 is a side view of the finishing machine.

Fig. 2 is an end view of same.

Fig. 3 is a diagrammatic sectional view of the roller.

The machine is constructed with a pattern roller A of mild steel, vulcanized rubber, compressed fibre, cotton or other suitable material on the surface of which the design or pattern is carved or engraved. The pattern roller A is pressed against a heated calendering roller B having a higher surface speed than the roller A the cloth to be treated passing between the rollers A and B. A nip or drag roller D is mounted at one side of the roller A and presses the cloth against the surface thereof so that there will be no slip between the cloth and the roller A. The cloth to be treated is carried on the roller C and passes therefrom over the drag rods E to the rollers A and B and is wound on to the batch roller C¹.

The pattern roller A is carried in bearings A¹ which are arranged to slide in the framing of the machine and can be adjusted by the screws a one at either end of the machine. Each screw is carried in a lever F fulcrumed at one end to the frame at f and carrying at the other end a pivoted depending rod G the lower end of which rests on the end of a horizontal lever H fulcrumed or pivoted to the frame at h. The other end of each lever H carries a sliding weight H¹ and this end is adapted to be raised by a lever J carrying a runner j. Each lever J is keyed or otherwise affixed on the shaft J¹ extending across the machine. An operating handle J² is mounted on the shaft J¹ so that by moving the handle J² the shaft J¹ can be rocked to raise or lower the ends of the levers H. The end of each lever H is provided with a recess h¹ in which the end of the lever J engages when in its upper position so that the lever H will be

held with its end raised against the action of the weight H¹.

When the ends of the levers H are raised the bearings A¹ will be lowered so that the roller A will be out of engagement with the roller B but when the levers J are moved to release the levers H, the weights H¹ will cause the roller A to press against the roller B.

The roller B is driven by the fast and loose pulley K, the belt fork k of which can be moved by either of the handles K¹ which are mounted on the shaft k¹ one at either end of the machine. The lever k² also affixed to the shaft k¹ transmits the movement of the latter to the fork k.

The roller A is driven from the roller B by the gear wheels L, L¹ and as these wheels are the same or approximately the same size, the surface speed of the roller A will be greater than that of the roller B since the diameter of the former is greater than that of the latter.

The spindle c of the batch roller C¹ is driven from the shaft of the roller A by the belt c¹ through the clutch c² so that the rotation of the roller C¹ can be stopped as desired by throwing out the clutch by the operating handle C².

The calender roller B is heated by the burner M which is provided with a gas inlet m and air inlets m¹. The nip roller D is mounted in horizontal bearings d and is kept in contact with the surface of the roller B by the spring, D¹.

What I claim as my invention and desire to protect by Letters Patent is:—

1. A machine for the production of ornamental finishes on textile fabrics comprising the combination with an embossing roller having a pattern thereon of a second heated roller having a polished surface and driven at a greater surface speed than the embossing roller, means for heating the second roller, bearings for the embossing roller, screws for adjusting said bearings, supports for the screws, means for applying pressure to said supports and a nip roller pressing against the embossing roller to hold the fabric in contact therewith.

2. A machine for the production of ornamental finishes on textile fabrics comprising the combination with an embossing roller having a pattern thereon of a second heated roller having a polished surface and driven at a greater surface speed than the embossing roller, means for heating the second roller, bearings for the embossing roller, screws for

adjusting said bearings, pivoted levers carrying the adjusting screws, depending rods carried at the ends of said levers, pivoted levers supporting the depending rods, weights on the levers to apply pressure to the embossing roller and a nip roller pressing against the embossing roller to hold the fabric in contact therewith.

3. A machine for the production of ornamental finishes on textile fabrics comprising the combination with an embossing roller having a pattern thereon of a second heated roller having a polished surface and driven at a greater surface speed than the embossing roller, means for heating the second roller, bearings for the embossing roller, screws for

adjusting said bearings, pivoted levers carrying the adjusting screws, depending rods carried at the ends of said levers, pivoted levers supporting the depending rods, weights on the levers to apply pressure to the embossing roller, a nip roller pressing against the embossing roller to hold the fabric in contact therewith, a roller from which the fabric is unwound, a batch roller to receive the fabric, means for driving the batch roller and a clutch to throw said driving means into and out of engagement.

In testimony whereof I have hereunto set my hand.

A. CROMPTON.
